UNITED STATES PATENT OFFICE.

RUDOLF LORENZ, OF ESSEN, GERMANY, ASSIGNOR TO FRIED. KRUPP AKTIEN-
GESELLSCHAFT, OF ESSEN-ON-THE-RUHR, GERMANY.

SELF-DISCHARGING CAR.

1,427,539.

Specification of Letters Patent. Patented Aug. 29, 1922.

Application filed February 9, 1921. Serial No. 423,849.

To all whom it may concern:

Be it known that I, RUDOLF LORENZ, residing at Essen, Germany, a citizen of the German Republic, have invented a certain 5 new and useful Improvement in Self-Discharging Cars, of which the following is a specification.

This invention relates to self-discharging cars discharging from the bottom and having bottom flaps opening automatically under the weight of the load and movable side walls resting with their lower edges upon the bottom flaps and being displaced by the latter on the discharging operation 10 and pivoted at their upper edges on fixed parts of the car. The object of the present invention is to so improve self-discharging cars of the type described as to enable a quick and reliable discharging even in the 15 case of extremely bulky material to be discharged.

One embodiment of the subject-matter of the present invention is illustrated in the accompanying drawing in which—

20 Fig. 1 shows a section through a self-discharging car constructed in accordance with the invention, ready for loading, and

Fig. 2 shows a similar section of the car in the discharged state.

25 The two bottom flaps B are connected, so as to admit of rotation, with the underframe A of the car by means of bearings a^1 arranged at either side of the longitudinal middle plane of the car. The bottom flaps

30 B are inclined toward the middle line where their respective lower edges b^1 bear against each other and they thus constitute a funnel-shaped hold. The two side walls C are suspended at their upper edges by means of

35 hinges c^1 to the stationary end walls A^2 of the car, their lower edges c^2 resting on the bottom flaps B. The conditions and respective dimensions are so chosen, that the lower edge c^2 of each side wall will, at any

40 position which the parts may assume, be disposed nearer to the middle line of the car than the bearings a^1 of the bottom flaps B.

45 When the car is ready for loading, the two bottom flaps B are connected to each other at their lower edges b^1 by means of a

locking device, such as hook b^2 and pin b^3 .

When the car is to be discharged, the locking device of the bottom flaps B is released, whereupon said flaps, by the weight of the 55 load, begin to swing down about the axis of the bearings a^1 and consequently open downwardly. The side walls C, acting likewise under the action of the weight of the load, follow the movement of the bottom flaps B 60 and swing outward in the direction indicated by the arrows x (Fig. 1) until they have attained the position illustrated in Fig. 2. Owing to this outward movement of the side walls C the space enclosed by them 65 before the bottom flaps opened, increases so that even very bulky materials may be satisfactorily and automatically discharged.

The discharging having been effected, the movable parts of the car are returned into 70 the position indicated in Fig. 1, whereupon the bottom flaps B are again connected to each other by means of the above-mentioned locking device.

I claim:

1. A self-discharging car having bottom flaps suspended on fixed parts of the car and movable side walls partaking of the discharging movement of said bottom flaps and suspended on fixed parts of the car, the 80 lower edges of said side walls resting upon the corresponding bottom flap at points lying nearer to the middle plane of the car than the points at which the corresponding bottom flaps are suspended. 85

2. A self-discharging car for material dischargeable with difficulty comprising side members and a plurality of bottom members opening downwardly on the discharge of material from said car, said side members 90 contacting with the contiguously mounted bottom members said side members automatically opening outwardly by the action of the bottom members when taking up a discharging position. 95

The foregoing specification signed at Essen, Germany, this 27th day of September, 1920.

RUDOLF LORENZ.

In presence of—

HANS GOTTMANN,
JOHANN DECKERS.
